S. A. NEIDICH

REVOLUTION COUNTING AND STOP MECHANISM

Filed June 23, 1925

FIG. IV.

INVENTOR:

SAMUEL A. NEIDICH,

*By Arthur E. Page,
Attorney.*

UNITED STATES PATENT OFFICE.

SAMUEL A. NEIDICH, OF EDGEWATER PARK, NEW JERSEY, ASSIGNOR TO NEIDICH PROCESS COMPANY, OF BURLINGTON, NEW JERSEY, A CORPORATION OF NEW JERSEY.

REVOLUTION COUNTING AND STOP MECHANISM.

Application filed June 23, 1925. Serial No. 39,160.

This invention was designed for use in the manufacture of coated webs, such as carbon paper for billing, duplicating and adding machines. Such fabrics are sold in 5 units of seventy-five lineal feet, but in rolls containing from one to twelve pieces, arranged as parallel plies, in accordance with the kind of machine in which they are to be used, but the length of each piece should 10 be aliquot to such unit length. Therefore, it is highly desirable to have means to limit the cutting of such fabrics to the precise aliquot lengths required, to avoid waste of the materials; and the object and effect of 15 my invention are to provide such means.

As hereinafter described; a convenient embodiment of my invention is accessory to a roller, hereinafter termed the measuring roller, over which such fabric is so progressed as to revolve that roller in accordance with the length of the fabric passed thereover. That accessory device includes an index dial, connected with said roller, by suitable gearing; so that the passage of each 20 such unit length of fabric effects one revolution of said dial. Said dial is arranged as the terminal of one side of an electric circuit and provided with a plurality of concentric circular series of electric contact pins; for instance in the form illustrated, 25 there are twelve such series, respectively including from twelve to one such pins; which are equally spaced in their respective series. Said contact dial is arranged to 30 cooperate with a terminal of the opposite side of said circuit which is conveniently mounted on a slide bar which is adjustable so that said terminal may be presented in registry with any one of the twelve series 35 of pins. Such arrangement renders said accessory device operative to close the electric circuit, by contact of said terminals, any number of times from one to twelve, during 40 each revolution of said dial, in accordance with the position to which said slide bar is set. In said embodiment of my invention; 45 said electric circuit includes a source of current and an electromagnetic tripping device for a clutch which is part of the mechanism 50 for progressing said fabric over said measuring roller and between shears so that it may be cut the proper length, when stopped, each time the circuit is closed as aforesaid.

That form of my device also includes convenient means enabling the operator to 55 readily reset the tripping mechanism and clutch to their normal operative positions, and my invention includes the various novel features of construction and arrangement hereinafter more definitely specified. 60

In said drawings, Fig. I is a diagrammatic elevation of a convenient embodiment of my invention.

Fig. II is a fragmentary vertical sectional view of said dial, and shows the connected position of said electric terminals, corresponding with the position thereof shown in Fig. I. 65

Fig. III is a fragmentary vertical sectional view of said electromagnetic tripping device. 70

Fig. IV is a fragmentary sectional elevation of said tripping mechanism in cooperative relation with the clutch mechanism and means for resetting the same. 75

In said figures; the measuring roller 1 is mounted to rotate in a suitable frame of which part is indicated at 2 in Fig. IV. Said roller 1 has the shaft 3 provided with the worm 4 engaged with the worm gear 5 which is rigidly connected with the shaft 6 which carries said contact dial 7. 80

Said dial 7 is arranged as the terminal of one side of an electric circuit with which it is connected by the conductor 8, and is 85 provided with twelve concentric circular series of electric contact pins 9; said series respectively including from twelve to one such pins; which are equally spaced in their respective series. Each contact pin 9 on said contact dial 7 is arranged to cooperate with the single spring terminal 10 which is arranged as the terminal of the opposite side of said circuit with which it is connected by the conductor 12. Said terminal 10 is conveniently mounted on the slide bar 13 which carries the insulating base 14 to which the upper end of said terminal 10 is rigidly connected. Said slide 13 is vertically adjustable in the bearing 16 which 90 is supported by the machine frame 2, in any convenient manner. It is to be understood that the arrangement is such that said terminal 10 may be presented in registry with any one of the twelve series of pins 95 100 so that said device is operative to close said

electric circuit by contact of said terminals 9 and 10, any number of times from one to twelve, during each revolution of said dial 7, in accordance with the position to which said slide bar 13 is set, in the radial guide bearing 16. As shown in Fig. I, said slide 13 is set in its uppermost position, with the upper edge of the bearing 16 in registry with the graduation 12' on said slide, which thus 10 presents said terminal 10 in registry with the twelve terminals 9 in the outermost circular series on said dial 7; so that, as thus adjusted, said device is operative to close said electric circuit by contact of said terminals 9 and 10 twelve times during a single revolution of said dial 7.

Said electric circuit, comprising said conductors 8 and 12, includes the source of current 18 and the electromagnetic tripping device 19, as diagrammatically indicated in Fig. I. As indicated in Fig. III; said tripping device 19 comprises the electromagnet 20 which is rigidly mounted in the casing 21, below the armature 22, which is 20 pivotally connected with said casing at its left hand end and conveniently by cone pointed screws in the opposite walls of said casing 21 which are parallel with the plane of section of Fig. III, and said armature is 30 normally upheld in the position shown in Fig. III by a suitable spring. In that position; said armature 22 is engaged by the movable latch 25 which is pivoted at its upper end to said casing and has a suitable 35 notch engaging the pin 26, projecting from the tripping lever 27 which is fulcrumed at 28 in said casing 21 and normally upturned to the position shown in Fig. III by the spring 30.

In the normal position of the parts shown in Figs. III and IV; said tripping lever 27 extends beneath the hook link 31 which then engages, in its notch 32, the stop projection 34 on the frame 2. Said link 31 is 40 carried by the clutch shifting yoke 35 which is fulcrumed at 36 and operatively connected with the groove hub 38 of the cone clutch member 39. Said clutch member 39 is connected with a suitable electric motor or other means for driving the fabric feed roller 40; which latter may be either directly or indirectly connected with the complementary conical clutch member 41; so that, when the parts are in the position 50 shown in Figs. III and IV; said roller 40 is rotated to progress the fabric 42 which is to be measured as aforesaid.

The construction and arrangement above described are such that whenever said electric circuit is closed to energize said electromagnet 20; said armature 22 is drawn down below the end of said latch 25 thus permitting the latter to be swung to the left by said pin 26 on the tripping lever 27, as 60 said lever 27 is drawn down under tension

of said spring 30; thus said tripping lever 27 is tilted by its spring 30 to trip said hook link 31 out of engagement with said projection 32, shown in Fig. IV. Thereupon, 70 said clutch member 39 is axially shifted, to the right in Fig. IV, by the spring 43 connected with the arm 45 on said yoke 35, to thus disconnect said feed roller 40 from its driving mechanism and stop the progression of the fabric 41 through the machine 75 after a predetermined length of such fabric has been passed over said measuring roller 1; such length being variably predetermined by the adjustment of said terminal 10. That is to say; each measured length of the 80 fabric 41 may correspond with from one-twelfth of a revolution of said dial 7, up to a complete revolution thereof. However, the dimensions specified are merely convenient to satisfy the trade demands for 85 the multiple carbon paper rolls aforesaid, and it is obvious that the relations of the measuring roller and dial may be different in accordance with the units of measurement desired. 90

When said mechanism has been thus automatically electrically tripped and stopped; said armature 22 is held down, in abnormal position, by said latch 25 which has been 95 swung over it by the pin 26 of the tripping lever 27 and, consequently, it is necessary to reset said tripping mechanism to the position shown in Fig. IV; to perform another measuring operation. I find it convenient to effect such resetting by means of the pedal 100 lever 47, which is normally upheld in the position shown in Fig. IV, by the chain 48 pendent from the spring 49 attached at its upper end to the frame member 2. Said chain 48 has the branch 51 connected at its 105 upper end with the arm 52 of said yoke 35, and is of such length that the first effect of depressing said pedal 47 is to reset said yoke to the position shown in Fig. IV with its hook lever 31 engaged with said frame projection 32, so as to detain the clutch device 110 in position to rotate said roller 1, until the tripping operation aforesaid is repeated. However, said chain 48 has the second branch 54 which is connected by the spring 115 55, with said tripping lever 27, so that further downward movement of said pedal 47 resets said tripping mechanism to its initial normal position shown in Fig. III.

Although I have found it convenient to 120 employ the contact dial mechanism aforesaid with the forms of tripping and clutch mechanism which I have illustrated; it is to be understood that it may be used in conjunction with either tripping mechanism or 125 clutch mechanism of other forms.

Therefore, I do not desire to limit myself to the precise details of construction and arrangement herein set forth, as it is obvious 130 that various modifications may be made

therein without departing from the essential features of my invention, as defined in the appended claims.

I claim:

- 5 1. In revolution counting and stop mechanism; the combination with a measuring roller; of driving mechanism for said roller, including a clutch mechanism comprising a spring normally tending to release said clutch and a hook arranged to hold said clutch in operative position until tripped; an index dial; means constituting said dial the terminal of one side of an electric circuit; a source of current included in said circuit; an electromagnetic tripping device included in said circuit, in cooperative relation with said clutch hook; a train of gearing operatively connecting said roller with said dial; including a worm driven by said 20 roller and a worm gear operatively connected with said dial; a plurality of concentric circular series of electric contact pins, carried by said dial; said series including respectively different numbers of pins, symmetrically spaced in their respective series; a terminal of the opposite side of said circuit, comprising a spring; means supporting said spring terminal, including an insulating base mounted on a slide bar; and a guide bearing for said slide bar, in radial relation with the axis of said dial; whereby said slide bar is adjustable to present said spring terminal in registry with any one of said several series of contact pins, to close the 25 electric circuit, by rotation of said dial, the number of times per revolution determined by the number of pins in such registered series, and thereby stop the rotation of said roller each time said circuit is closed.
- 40 2. In revolution counting and stop mechanism; the combination with a measuring roller; of driving mechanism for said roller, including a clutch mechanism; an index dial; means constituting said dial the terminal of one side of an electric circuit; a source of current included in said circuit; an electromagnetic tripping device included in

said circuit, in cooperative relation with said clutch; a train of gearing operatively connecting said roller with said dial; a plurality of concentric circular series of electric contact pins, carried by said dial; said series including respectively different numbers of pins; a terminal of the opposite side of said circuit, comprising a spring; means 50 supporting said spring terminal, including a slide bar; and a guide bearing for said slide bar; whereby said slide bar is adjustable to present said spring terminal in registry with any one of said series of contact pins, to close the electric circuit, by rotation of said dial, the number of times per revolution predetermined by the number of pins in such registered series, and thereby stop the rotation of said roller such predetermined number of times per revolution.

3. In revolution counting and stop mechanism; the combination with a measuring roller; of driving mechanism for said roller; an index dial; means constituting said dial the terminal of one side of an electric circuit; a source of current included in said circuit; an electromagnetic tripping device included in said circuit, in cooperative relation with said driving mechanism; means 70 operatively connecting said roller with said dial; a plurality of concentric circular series of electric contact pins, carried by said dial; said series including respectively different numbers of pins; an adjustable terminal 75 of the opposite side of said circuit; whereby said adjustable terminal is movable to register with any one of said several series of contact pins, to close the electric circuit, by rotation of said dial, the 80 number of times per revolution predetermined by the number of pins in such registered series, and thereby stop the rotation of said roller such predetermined number of times per revolution. 90

In testimony whereof, I have hereunto signed my name at Burlington, New Jersey, this 19th day of June, 1925.

SAMUEL A. NEIDICH.

Certificate of Correction.

It is hereby certified that in Letters Patent No. 1,600,991, granted September 28, 1926, upon the application of Samuel A. Neidich, of Edgewater Park, New Jersey, for an improvement in "Revolution Counting and Stop Mechanism," errors appear requiring correction as follows: In the drawing, Fig. 1, strike out the reference numeral "12'" and the line leading therefrom; page 2, line 9, for "12'" read 12, and line 23, for the misspelled word "regidly" read *rigidly*; and that the said Letters Patent should be read with these corrections therein that the same may conform to the record of the case in the Patent Office.

Signed and sealed this 2d day of November, A. D. 1926.

[**SEAL.**]

WM. A. KINNAN,
Acting Commissioner of Patents.
